(57) **CLAIM**

The ornamental design for a bottle, as shown and described.

DESCRIPTION

FIG. 1 is a top isometric view of a bottle showing my new design;

FIG. 2 is a left elevational side view thereof;

FIG. 3 is a right elevational side view;

FIG. 4 is a front elevational view;

FIG. 5 is a rear elevational view;

FIG. 6 is a top view thereof; and,

FIG. 7 is a bottom view thereof.

The dotted lines illustrate portions of the bottle that form no part of the claimed design.
